UNITED STATES PATENT OFFICE

107,749

DESIGN FOR A COMBINATION BOOKEND,
HUMIDOR, AND ASHTRAY

Hamilton O. Cornwall, New York, N. Y.

Application August 31, 1937, Serial No. 71,403

Term of patent 3½ years

To all whom it may concern:

Be it known that I, Hamilton O. Cornwall, a citizen of the United States, residing at New York, in the county of New York and State of New York, have invented a new, original, and ornamental Design for a Combination Bookend, Humidor, and Ashtray, of which the following is a specification, reference being had to the accompanying drawing, forming part thereof.

Fig. 1 is a perspective view of a combination bookend, humidior and ashtray showing my new design.

Fig. 2 is a top plan view.

Fig. 3 is a side elevation.

I claim:

The ornamental design for a combination bookend, humidior, and ashtray, as shown.

HAMILTON O. CORNWALL.
